HINGE CONSTRUCTION FOR SWINGING
DOORSArthur F. Baum and Axel H. Anderson, Elkhart,
Ind., assignors to Henry Weis Manufacturing
Company, Inc., Elkhart, Ind.

Application March 2, 1942, Serial No. 432,920

4 Claims. (Cl. 16—154)

This invention relates to doors and particularly to swinging doors for toilet and other compartments, and among other objects aims to provide a door which will remain open when the compartment is unoccupied, but will remain closed without the use of a lock when the compartment is occupied.

The nature of the invention may be readily understood by reference to one illustrative construction embodying the invention and shown in the accompanying drawing.

In said drawing:

Fig. 1 is a diagrammatic plan view of a compartment showing various door positions.

Fig. 2 is an elevation of the door.

Fig. 3 is a plan section of an enlarged scale of the lower door hinge, taken on the plane 3—3 of Fig. 2.

Fig. 4 is a vertical section of the hinge taken on plane 4—4 of Fig. 3; and

Fig. 5 is a diagram showing a development of the door-operating cam.

It is often desirable to prevent the locking of doors to toilet and other rooms and compartments. This applies, for example, to hospitals and other institutions where patients and particularly mental patients often attempt to lock doors against entrance of attendants. It also applies to kindergartens and elementary schools. The illustrative door remains shut without locking when the compartment is occupied, but when unoccupied it automatically opens and remains open. This is of great practical importance. In the absence of a lock positively to prevent entrance of others, there should be reasonable preservation of privacy. Except when the compartment is occupied, the door tends to open and to remain open. A closed door therefore indicates occupancy of the compartment and thereby provides reasonable protection against unintentional interruption of privacy.

The door-operating forces in this case are components of gravity, and a gravity type of door hinge may advantageously be used for this purpose. As here shown, the weight of the door 10 is carried on a lower hinge 11 embodying a cam 12 whose upper cam edge 13 (on which the weight of the door rests) cooperates to develop the door-operating forces. Cam 12 is circular in section and its edge 13 forms a circular track or bearing surface inclined in certain regions to provide a component of force tending to swing the door. Such force is created by the camming action of the inclined surface (under the weight of the door) against a relatively movable bear-

ing member in the form of an anti-friction roller 14. In the present case, the cam 12 is stationary and the roller 14 is movable with the door around the upper surface 13 of the cam.

By inverting the cam and bearing member the latter may be made stationary and the former axially rotatable. The door-operating forces may also be created by a spring which creates pressure between the bearing member and the inclined cam face.

The roller 14 is, in this instance, carried on a door pintle 15 appropriately connected with the lower edge of the door and centered in a bushing 16 (concentric with cam 12) and supported by the stationary hinge member 17. The stationary hinge member 17 is in the form of a housing enclosing the cam and roller and having a top 18 which provides an additional bearing 19 for the pintle. The bottom 20 of the housing advantageously conforms with the contour of the bottom of the cam 12 and the latter is clamped in position against such bottom by means of the screw-threaded extremity 21 of reduced section on bushing 16, which projects through registering central openings in the cam 12 and bottom 20. A nut 22 screwed on the threaded extremity cooperates to clamp cam 12 in position in the hinge member 17.

The general details of construction of the above hinge member 17 may advantageously be like those in Jones et al. Patent No. 1,920,509.

The contour of the surface 13 of the cam is in this case designed to exert a rotating force on the door tending to open the same when the door is in a position slightly ajar. This position is indicated at 23 in Fig. 1 and should preferably be close enough to closed position (represented in dotted lines at 24, Fig. 1) that egress from the compartment would be impossible without opening the door beyond the critical position 23. In the present case such position represents a door opening of about 6 to 8 inches. In other words, when the door is opened beyond position 23, as it must be in leaving the compartment, the door will automatically swing open completely. The surface on the cam is furthermore designed to close the door when it is moved inside the position 23; that is, closer to closed position than the position 23.

In Fig. 5 is illustrated in developed form one contour for cam 13 for effecting the aforesaid operation. The high point 25 of the cam represents the position 23. The downward slope 26 serves to create the opening component of force. Such slope extends in this case to door-open po-

sition 27 which is approximately 90 degrees from closed position. The angular extent of the sloping surface 26 depends upon the angular displacement between open and closed position. In ordinary compartments this may be 90 degrees, but in some cases it may be almost 180 degrees. The short downward slope 28 extending in the opposite direction from high point 25 provides the closing component of force. Its angular extent depends, as above stated, upon the angular displacement of the critical position 23. To minimize shock or slamming of the door against the wall or stop when it reaches open position, the lower extremity of the inclined surface 26 preferably terminates a notch or pocket 29 in which roller 14 seats and by means of which its opening movement is arrested. To reduce the momentum of the door as it approaches open position, the inclination of cam surface 26 may advantageously be reduced adjacent notch 29. The low point 30 for inclined surface 28 is preferably located slightly beyond door-closed position (as shown in Fig. 5) to create a continuous component of force to hold the door shut.

The door thus tends to open and until it is manually closed to a position beyond the critical point 23, i. e. high point 25 of the cam from which position it will automatically close and remain closed without the necessity of locking. Resistance to opening of the door is exerted until the latter is pushed beyond the point 23. On leaving the compartment, the occupant must move the door well beyond the position 23 thereby changing the force on the door to an opening force which automatically opens the door and holds the door open. It resists closing until moved slightly beyond position 23.

The illustrative cam member is advantageously designed to be universally applicable for doors opening with either clockwise or counter-clockwise rotation, that is, for inwardly or outwardly swinging doors and for doors with the hinge on the right or left hand edge. For this purpose duplicate or reversely arranged inclined surfaces 31 and 32 are provided on the opposite side of door-open position 27 together with a low point 33 corresponding to low point 30. The portion 34 of the cam edge beyond the low points 30 and 33 is, in the present instance, idle. The angular extent of the idle surface 34 depends upon angle included between door-open and door-closed position. Inclined surfaces 31 and 32 function when the door opens in a counter-clockwise direction. While the critical position 23 may be adjusted (within limits) simply by changing the rotative adjustment of cam 12 inside housing 17, it is preferable to limit the extent of adjustment to avoid slamming of the door against the wall or stop when it moves to open position. Preferably, opening movement of the door should be arrested by engagement of the roller 14 in notch 29 and not by contact of the door with the adjacent wall or with a bumper. To adapt the hinge for a door opening outwardly or hinged along its left hand edge, it is only necessary to change the relative positions of the cam 12 and roller 14 from the positions shown in Fig. 4. This is easily done by simply turning the pintle 15 180° relatively to the door so that the roller 14 drops almost into the low point 33 (instead of 30) when the door is in closed position and rolls down inclined surface 31 (instead of 26) to low point 27 corresponding to open position of the door. With the hinge thus arranged the door will open outwardly in Fig. 1 instead of inwardly as there

shown. The hinge can of course be mounted on a fixed frame member at the left hand side of the door with the roller engageable nearly with the low point 30 or 33 when the door is in closed position, depending on whether the door is to swing in or out in opening, as will be readily understood. In all cases the roller engages the low point 29 when the door is in open position.

Any appropriate form of upper hinge 35 may be employed. Various forms are available on the open market and its details form no part of the present invention.

Obviously, the invention is not limited to the details of the illustrative construction since these may be variously modified. Moreover, it is not indispensable that all features of the invention be used conjointly since various features may be used to advantage in different combinations and sub-combinations.

Having described our invention, we claim:

1. A hinge construction for mounting a swinging door member on a frame member comprising a bearing element secured to one of said members and an arcuate cam track element secured to the other member, said elements being concentric and adapted to move relatively one on the other when the door member is swung between open and closed positions, said cam track element having a high point positioned to be engaged by the bearing element when the door member is too nearly adjacent to full closed position to pass a person and having on each side a downwardly inclined surface for automatically moving the bearing element to positions corresponding to full open and full closed positions respectively of the door member, whereby swinging the door member sufficiently open to pass a person will cause the door member to tend automatically to swing to full open position and whereby the door member will tend automatically to swing to full closed position only when moved too close to full closed position to pass a person.

2. In a hinge for mounting a swinging door member on a frame member, a cam coaxial with the hinge axis secured to one of the members and having a recess therein for receiving a bearing element secured to the other member to hold the door member in open position and having arcuate cam surfaces coaxial with the hinge axis and upwardly inclined from opposite sides of said recess and extending in opposite directions from said recess and around the hinge axis to adapt the hinge to doors opening with either a clockwise or a counter-clockwise swinging movement, a notch beyond the upper end of one of said inclined surfaces for receiving said bearing element to hold a clockwise opening door in closed position, and a notch beyond the upper end of the other inclined surface for receiving said bearing element to hold a counter-clockwise opening door in closed position.

3. In a hinge for mounting a swinging door member on a frame member, a cam coaxial with the hinge axis secured to one of the members and having therein a single recess for receiving a bearing element secured to the other member to hold the door member in open position and having arcuate cam surfaces coaxial with the hinge axis and upwardly inclined from opposite sides of said recess and extending in opposite directions from said recess and around the hinge axis to adapt the hinge to doors opening with either a clockwise or a counter-clockwise swinging movement, a notch beyond the upper end of one of said inclined surfaces for receiving said

bearing element to hold a clockwise opening door in closed position, and a notch beyond the upper end of the other inclined surface for receiving said bearing element to hold a counter-clockwise opening door in closed position, whereby regardless of the direction in which the door is arranged to open the bearing element will be received in the single recess when the door is open, and whereby the bearing element will be received in one or the other of the two notches when the door is closed, depending on whether the door is arranged to swing clockwise or counter-clockwise in closing.

4. A hinge construction for mounting a swing-door member on a frame member comprising a bearing element secured to one of said members and an arcuate cam track element secured to the other member, said elements being concentric and adapted to move relatively one on the other when the door member is swung between open and closed positions, said cam track element having two circumferentially spaced high points, one positioned to be engaged by the bearing element of a door member arranged to open in a clockwise direction and the other positioned to be engaged by the bearing element of a door member arranged to open in a counter-clockwise direction, each of said high points being so located that when it is engaged by the bearing ele-

ment the door member will be too nearly adjacent to full closed position to pass a person, and each high point having on both sides of it a downwardly inclined surface, two of said surfaces being relatively long and extending to a single recess for receiving said bearing element to hold a door member in open position regardless of the direction in which the door member is arranged to swing to closed position, and each of the other two of said surfaces being relatively short and each extending to a separate notch, one of said notches being adapted to receive said bearing element for holding in closed position a door member arranged to swing clockwise to closed position and the other of said notches being adapted to receive said bearing element for holding in closed position a door member arranged to swing counter-clockwise to closed position, whereby, regardless of the direction in which the door member is arranged to swing, swinging the door sufficiently open to pass a person will cause the door member to tend automatically to swing to full open position and whereby the door member will tend automatically to swing to full closed position only when moved too close to full closed position to pass a person.
